UNITED STATES PATENT OFFICE.

EDGAR F. HATHAWAY, OF WELLESLEY, MASSACHUSETTS, ASSIGNOR TO SHAWMUT ENGINEERING COMPANY, OF BOSTON, MASSACHUSETTS, A CORPORATION OF MASSACHUSETTS.

SPOOL-SUPPORTING MEANS FOR TUBE FRAMES.

Application filed May 6, 1926. Serial No. 107,068.

This invention relates to tube frames such as are used in tuft weaving of fabrics like Axminster carpets, and is intended to provide means for supporting the yarn-spools 5 of such frames for wide looms so as to secure equal or uniform rotation of the plural spools, while making provision for easy and rapid removal of either spool section from its bearing supports.

In the case of tube frames for wide or seamless Axminster rugs, it is customary to employ two or more yarn spools co-axially arranged end to end, with provision for interlocking their adjacent ends to produce 15 uniform or equal rotation of the spools, but usually the interlocked ends are made as male and female members so that flexibility of arrangement is limited by reason of the fact that the spools are not universally interchangeable.

It is the object of the present invention to provide a very simple construction and which, at the same time, facilitates speed in handling, produces equal rotation of the 25 spools and makes it possible to interlockingly connect any spool in storage with any other spools when it becomes necessary to reverse or interchange the spools for any reason.

With these and other objects in view the invention comprises, generally speaking, an intermediate spool-supporting bracket in which is independently mounted a rotatable coupling member constructed to have quick 35 detachable interlocking connection with the adjacent ends of both yarn-spools between which it is located for the purpose of rotatably supporting both spools and coupling them together to secure uniform or equal 40 rotation thereof.

This and other features of the invention will be more particularly described in the following specification and will be defined in the claims hereto annexed.

In the accompanying drawings I have 45 illustrated a cheap and convenient construction and arrangement embodying the principles of this invention, in which:

Figure 1 is a front elevation, partly in 50 section, showing a complete tube frame with interlocked portions broken away to show

the interior construction to which the invention relates.

Figure 2 is a front elevation of the specific form of coupling member illustrated in 55 Figure 1.

Figure 3 is an end elevation of the same in its supporting bracket.

Figure 4 is a vertical central section through one end of one of the yarn-spools. 60

Figure 5 is an end elevation of the head shown in Figure 4.

Figure 6 is a vertical central section through another modification showing a contractile and expandable brake mechanism 65 which serves the double purpose of retarding rotation of the spool and preventing endwise displacement of the coupling member during its rotation.

Figure 7 is an end elevation, partly in 70 cross section, of the construction of coupling member and bearing bracket shown in Figure 6.

Figure 8 is a vertical section showing a modified construction and arrangement of 75 the middle bearing member with adjacent spool ends supported thereon.

Figure 9 is a side elevation of the upper portion of one of the middle bearing brackets illustrated in Figure 8, with the coupling 80 spline removed.

Figure 10 is a detail showing, in cross section, the coupling member and the journal member of the spool splined together for equal rotation.

Figure 11 is a detail similar to Figure 8 showing one of the spools tilted and pushed inwardly to permit removal.

The construction embodying the principles of this invention is applicable in a variety 90 of ways to accomplish different objects for which the invention is intended. It provides a construction facilitating the removal of the yarn spools from the tube-frame, as well as a construction for coupling adjacent

yarn-spools together to secure equal rotation thereof in winding the yarn, and it also permits the use of a universal spool, that is, one that can be used not only in different positions in the same tube frame 100 and that is reversible end for end therein, but also one that may be used in a single

spool tube-frame where, ordinarily, a spool with simple bearing pintle journals is employed.

In the form of the invention shown in Figures 1 to 6 the main parts of the tube frame, except the middle bearing construction, embrace the usual longitudinal carrier bar 1, to which are secured the row of spaced tuft-tubes 2 for delivering the yarn to the fabric being woven, end hangers embracing a chain-penetrating arm 3, a hook-latch 4, a spool-bearing bracket or ear 5, in this case with an open bearing for the spool, and associated therewith a journal-retaining arm or latch 6 which normally overhangs the spool journal on the open side of the bearing and is pressed into operative position by an expansion spring 7, which is interposed between the keeper 6 and the hook-arm or latch 4, to yieldingly force them apart.

For weaving seamless rugs of double, treble or quadruple width, tube-frames are usually provided with an aligned series of single breadth spools, the two outside journals of which are mounted in brackets, more or less similar to the brackets 5, while the interior journals are mounted in middle stands or brackets mounted on the carrier-bar at proper intervals to be interposed between adjacent ends of adjacent spools.

In the present case I have shown a yarn-spool whose barrel 11 is in the form of a metallic tube to which are secured end heads 35 12 whose central portion is depressed to form a hollow boss 12^a, fitting inside the barrel to which the barrel is secured. Centrally of the connecting bosses 12^a are secured, by riveting or otherwise, suitable 40 stub shafts or pintle journals 13, all of which, in this case, are of substantially the same dimensions to allow the spool to be reversed end for end to correspondingly change the pattern or to be placed in any 45 desired order of arrangement in a multiple spool tube-frame.

The central bearing bracket 8, in this case, comprises two sheet metal arms riveted or spot-welded together, the upper portion 50 of said bracket members being provided with aligned bearing openings whose edges, in this case, are turned outwardly to form annular bearing flanges 8^a. At their lower ends these bracket plates or members are 55 severed to permit the formation of an eye to receive a bearing rod or pintle 8^c, a portion of the lower ends being continued down to form projecting heels 8^b, engaged with a flat or leaf spring 9 projecting across 60 an opening in its support 10, and held in place by headed screws 10^a, the further details of which need not be explained as details of this construction form the subject matter of another application. This is a 65 construction which permits the middle bear-

ing bracket to be swung to either side of its normal position to facilitate the removal of the spool journal, while being normally held by spring tension in its vertical or upright position.

Mounted inside the bearing opening of the upright stand 8 is a relatively short rotatable bearing member 15, whose outer ends, in this form, project inside the hollow or cupped ends of the heads 12 of the spools and afford a bearing support for the adjacent ends of the spools. This bearing and coupling member is centrally bored to allow the journals 13, of the spools, to pass into its interior and preferably this central bore 75 is made somewhat larger than the diameter of the pintle to allow the spool to be tipped up or inclined when being removed without binding on the journal. The middle bearing member in this form is provided with an annular external rib 16, which projects into the annular recess formed between the two flanged plates, thereby preventing endwise displacement of the rotatable bearing member 80 with relation to its supporting bracket 8, while not interfering with its rotation.

In this case the coupling member comprises a longitudinal pin 17 driven through a small eccentrically located bore in the member 15, with its ends projecting beyond the ends of the member 15 to penetrate oppositely aligned holes 12^b punched in the offset or cupped portion of each head, there being preferably an annular series of such holes to permit circumferential adjustment 95 of one spool in relation to the other.

It will be observed that the bearing opening for the reception of the rotatable coupling member 15 is closed and that the coupling member itself is permanently mounted 105 in its bearing bracket but is detachably connected or engaged, at its opposite ends, with the adjacent ends of the yarn-spools. This construction permits the removal of either yarn-spool from the middle bearing 110 without depriving the other spool of its bearing support.

To remove either of the spools shown, the operator releases the keeper 6 in order to lift the journal out of the bearing bracket 5, so as to permit withdrawal of the spool in somewhat tilted or oblique position endwise from its interior bearing member 15. The circular arrangement of locking holes 12^b permits any desired degree of rotative 120 adjustment between the two spools to bring their free yarn ends in to a common line or position.

In Figures 7 to 10 is shown another modification of the middle bearing bracket in 125 which the rotatable bearing member 25 is made to permit axial displacement of the rotatable bearing member 25 in its supporting bracket 18. In this case the rotatable bearing member 25 is provided with a 130

medial annular circumferential groove 25^a in which is seated a split ring 27 of wire which normally contracts into the groove but is so dimensioned as to project about 5 half its diameter beyond the circumferential surface of the member 25. The plates which form the bracket 18 are, in all respects, similar to the plates 8, except that the extended flanges 8^a may be omitted and the two plates, 10 adjacent to the bearing orifice, are spread apart to form an annular recess or channel of sufficient depth to allow the wire spring 27 to expand entirely into it. The annular groove 25^a is somewhat V-shaped so that 15 substantial pressure endwise upon the member 25 causes the split wire ring 27 to expand into the annular recess or channel of the stand 18, the sides of the groove 25^a having a cam-like action to effect such expansion. When expanded to this position 20 the member 25 may be moved endwise to facilitate disengagement and removal of the spool. This action is particularly advantageous where the spools, as is often the case, 25 are provided with circumferential outwardly projecting flanges 12^a.

The method of splining or coupling the two spools together in this form of the invention differs in detail from that previously 30 described. In this case the central bore of the member 25 is longitudinally slotted to form a keyway in which is placed a spline or key 26, adapted to project into notches 13^a of the journal members.

35 It will be understood that in both cases the coupling spline may be driven endwise from the rotatable coupling member to allow independent rotation of the spools because, in some cases, mills prefer to dispense with 40 a positive coupling connection and allow the spools to rotate independently of one another. In that case the member 25 forms a common bearing member for the two spools and is endwise displaceable to facilitate the 45 removal of either spool. The spline can be readily inserted at any time to couple the spools rotatably together.

In Figures 6 and 7, I have shown a construction of middle bearing which is adapted 50 also to provide a braking or retarding action to frictionally retard the spools and hold them against external rotation. Brake devices for this purpose have been commonly employed to press against the outer heads of 55 the spools, but this construction is easily applicable to the middle bearings as well. In this case the rotatable bearing member 21 is mounted in an upright stand 8, similar to that shown in Figure 1, but this stand 60 has its flanges 8^a cut through for a part of their circumference to allow the insertion of arcuate brake shoes 23, which may be made of raw hide, fibre or other suitable material, and these arcuate shoes are kept 65 in place and pressed against the rotary bear-

ing member 21 by means of a circumferential split ring 24, which is seated in external or circumferential grooves, formed in said shoes, to properly position them and, by their contractile force, exert the desired degree of pressure upon the rotating member 21. In this case the rotatable bearing member 21 is shown as provided with annular grooves 21^a of approximately V shape, into which project the wedge shaped brake shoes 70 75 23. This form increases the braking action and at the same time permits the brake shoes, with their encircling expansible springs, to act as an expansible key or spline to allow endwise displacement of the bearing member 21, by pressure on one end thereof.

Coupling pins 22, driven through small bores in the member 21 serve, in this particular form, not only to couple the two 80 spools together to rotate in unison, but also form the actual support for the spool members 20. In this case I have shown the ordinary wooden spool 20 with its wooden head or flange 20^a, instead of the metallic 85 spool previously described. The end faces of these spools are provided with an annular series of bored openings 20^b to receive the coupling pins 22. In this case, of course, removal of the coupling pins would deprive 90 the spools of their rotatable support, in which respect this form differs from the other forms above described, but in all the forms shown and described the rotatable bearing member, mounted in the middle 95 bracket or stand, is capable of affording both 100 a bearing support for the two spools as well as a coupling connection between them.

What I claim is:

1. In a tube frame for tuft weaving, the combination with a longitudinal carrier-bar having spool-bearing brackets at its ends, of a medial bearing bracket formed with a closed annular bearing, a rotatable coupling member mounted in said bearing and having releasable coupling connection at both ends with the adjacent ends of adjacent yarn-spools to insure equal rotation of both spools while allowing either spool to be removed without depriving the other of its bearing support.

2. In a tube frame for tuft weaving, the combination with a longitudinal carrier-bar having spool-bearing brackets at its ends, a rotatably supported spool-coupling member 110 interposed between adjacent ends of two spools and having releasable coupling engagement with both spools, said coupling member being movable in a direction lengthwise of the spools to facilitate the removal 115 of spools from the tube frame.

3. In a tube frame for tuft weaving, the combination with a longitudinal carrier-bar having spool-bearing brackets at its ends, one or more middle bearing brackets inter- 120 125 130

posed between two spools, a rotatable coupling member mounted in said middle bearing bracket and having detachable coupling connection with each of said spools and 5 means for engaging the coupling member with its bracket to normally prevent axial displacement thereof in the bracket during rotation.

4. A middle bearing bracket for tube- 10 frame yarn spools embracing in combination an upright stand adapted to be mounted on a tube-frame carrier-bar so as to be interposed between two aligned spools, a rotatable coupling member mounted in a bearing 15 opening formed therein and having, at both ends, means adapted to form detachable coupling engagement with two adjacent spools to secure equal rotation of both spools for the delivery of yarn.

5. A spool-bearing bracket for a tube frame embracing an upright bearing stand, a rotatable member mounted therein and provided with means for rotatively coupling it with the adjacent ends of spools that are 25 coaxially disposed on opposite sides of the stand, said member being axially bored for the reception of adjacent spool journals, thereby permitting reversal of either spool end for end.

6. A spool-bearing bracket for a tube frame embracing in its construction an upright bearing stand adapted to be interposed between adjacent coaxial spools, a spool coupling member rotatably mounted therein 35 and formed to have detachable coupling connection with two adjacent coaxial spools, means for engaging the coupling member with its bracket to retain the coupling member against axial movement when rotating, 40 while permitting axial displacement under endwise thrust.

7. A spool bearing bracket for a tube frame embracing an upright stand provided 45 with an annular bearing, a spool-coupling member rotatably mounted therein and formed to have coupling connection with the

adjacent ends of coaxially arranged spools, means for normally retaining said coupling member against axial displacement when rotating, said means embracing circumferential outwardly expansible means engaging an annular groove formed in the circumferential surface of the coupling member.

8. A spool-supporting bracket for a tube frame embracing an upright stand provided 55 with a bearing opening a spool-bearing member rotatably mounted in said bearing opening and formed to project in part into recesses in the ends of aligned yarn spools and to receive within itself the projecting 60 journals of such yarn spools.

9. In a tube frame the combination with a carrier-bar having at its ends spool-bearing brackets and one or more middle brackets, a plurality of yarn spools mounted in said 65 brackets end to end, each yarn spool having journals of like construction at both ends and means rotatably supporting the middle bearings to detachably couple together the adjacent ends of the spools to cause them to 70 rotate in unison.

10. A spool-bearing bracket embracing an upright stand formed with a flanged bearing, a spool-supporting member rotatably mounted therein and affording coupling connection between two adjacent spools, radially contractible brake means mounted on 75 said stand to have frictional engagement with said bearing member to frictionally retard rotation of the spools.

11. A middle spool bearing stand for a tube frame adapted to be interposed between the adjacent heads of two spools and afford support for the spools, spool-retarding means embracing radially movable brake 85 shoes, and a contractible spring exerting inward pressure on said brake shoes to retard rotation of the spools.

In witness whereof, I have subscribed the above specification.

EDGAR F. HATHAWAY.
